UNITED STATES PATENT OFFICE.

ERNEST A. LOWE, OF NORTH PLAINFIELD, NEW JERSEY, ASSIGNOR TO AUTOMATIC SPRINKLER COMPANY OF AMERICA, OF NEW YORK, N. Y., A CORPORATION OF NEW YORK.

AUTOMATIC FIRE-ALARM DEVICE.

1,401,914.

Specification of Letters Patent. Patented Dec. 27, 1921.

Application filed December 27, 1918. Serial No. 268,443.

To all whom it may concern:

Be it known that I, ERNEST A. LOWE, a citizen of the United States, and resident of North Plainfield, county of Somerset, State 5 of New Jersey, have made a certain new and useful Invention Relating to Automatic Fire-Alarm Devices, of which the following is a specification, taken in connection with the accompanying drawing, which forms 10 part of the same.

This invention relates to fire alarm devices preferably adapted to make a distinctive audible alarm signal under fire conditions as when the temperature of the adjoining 15 premises rises at an excessive rate. This may be effected by using any suitable compensated thermostat such as a vented air thermostat, and the apparatus may also comprise any desired form of audible alarm 20 signal, such for instance, as a siren, gong, whistle or a diaphragm alarm of the type described herein in which, if desired, the vibrator or contact member may be actuated by impulses of varying periodicity or amplitude 25 or the resulting sound may be more or less damped or diminished periodically or at more or less regular time intervals so as to give a characteristic sound which can be easily recognized as an alarm signal. Any 30 desired form of driving or motor device may be used in connection with such an audible signal and a spring, weight, electric or pneumatic driving device may be used if desired. A heavy spring used in connection with such 35 a vibrated diaphragm type of alarm gives good results and makes possible a self contained device of relatively light weight which may be put in place at the desired intervals around the premises to be protected.

In the accompanying drawing showing in a somewhat diagrammatic way illustrative embodiments of the invention,

Figure 1 is a vertical sectional view.

Fig. 2 is a transverse or horizontal sectional view taken substantially along the line 2-2 of Fig. 1.

Fig. 3 is a partial section taken along the line 3-3 of Fig. 1.

Fig. 4 is a sectional detail taken along the line 4-4 of Fig. 1.

Fig. 5 is another sectional detail taken substantially along the line 5-5 of Fig. 2; and

Fig. 6 is a partial sectional view showing 55 a modified construction.

The device may advantageously comprise a rigid frame which may, if desired, be formed of the posts or frame members, such as 39, 39, bolted or otherwise secured to the frame members, such as 38, and also to the front plate 77 to which they may be detachably secured as by the screws or bolts 40. A casing, such as 2, of sheet metal or other suitable material may be secured to the frame as by suitable screws 8 indicated which may also secure the casing to the cover 4 or other part of the air chamber of the device. This casing may have a support 3 secured thereto in any desired way so as to 70 conveniently hold the device in position by screwing this support against a wall preferably so that the air chamber of the device is brought adjacent the ceiling 1 of the room where it usually responds more quickly to 75 the currents of highly heated air which are caused by a starting fire. Any desired form of thermostat may be used to actuate the devices and as indicated an air thermostat may be used for this purpose and may advantageously comprise a metallic air chamber mounted in any suitable position in connection with the apparatus. The air chamber may, if desired, be formed of a cover member 4 of generally arched or dome form having a flange 7 bent down adjacent the casing 2, as shown in Fig. 1. This flange may be soldered or otherwise secured to a support plate 5 having a similar flange 6, if desired, which may of course be rigidly secured to 80 the frame plate 38 as by one or more connecting members 102. The support plate may be formed with one or more apertures, such as 84 and if desired a relatively flexible metallic or other diaphragm 9 may be secured in such position so as to coöperate with this air chamber and be actuated by the air pressure developed therein as by securing this thin metallic detector diaphragm to the apertured support plate. 100 This may be readily done by clamping the diaphragm between the support plate and a guard plate 10 of brass or other suitable material secured in position as by the screws 11 around its periphery so that the diaphragm is allowed a limited movement between these two apertured plates which prevent its being unduly bent or distorted by

the air pressure differences caused by the changes of temperature to which the air chamber is subjected. To form a rate-of-rise thermostat this air chamber is vented in any suitable way as by forming the pin hole vent or aperture 103 therein which is of course considerably exaggerated in the drawing for the sake of clearness. The capacity of this vent is of course so arranged with respect to the size of the air chamber that it will take care of the normal slow temperature changes to which the device is subjected under normal conditions of the protected premises without developing any substantial or considerable pressure difference within the chamber. When, however, an excessive rate of temperature rise occurs, such as corresponds to an incipient fire, the expansion of the air can no longer be substantially equalized by escape through this vent and the excess pressure acting on the diaphragm forces it outward so as to actuate the alarm signal mechanism.

The alarm signal may, if desired, comprise an alarm diaphragm, such as 79, which may as indicated in Figs. 1 and 5 be clamped or screwed against the front plate 77 to which the horn member 80 may be simultaneously attached, if desired. The contact member 81 may be secured to this diaphragm in any desired way as by the nuts 82 so that this contact member properly co-operates with a toothed vibrator disk or member 73 secured in any desired way on the vibrator shaft 66 and having sufficient weight to give the desired inertia effects to produce the alarm signal most effectively. This vibrator may be driven by any suitable motor devices, such, for instance, as the spring motor shown which may as indicated in Fig. 2 comprise the heavy motor or driving spring 71 co-operating with the driving shaft 62 on which the driving wheel 61 is mounted so as to co-operate with the pinion 63 on the intermediate shaft 67 having secured thereto the winding ratchet 68. The co-operating pawl 69 may be normally held in engagement with this ratchet as by the spring 70 and may be pivoted or otherwise connected to the intermediate wheel 64 which may mesh with the vibrator pinion 65, see also Fig. 5. This vibrator member or disk may have secured thereto a detent wheel or device 76 having a series of teeth around its periphery with which may co-operate the latch of the detent mechanism. This is shown in Figs. 1 and 2, the latch 35 having a cut-away portion so that when in the holding or normally set position shown in Fig. 2 this latch is engaged by one of the detent teeth 76 to prevent rotation of the vibrator. This latch may be revolvably mounted in the brackets 34, 37 secured to the front plate or other frame member as by posts such as 41, as indicated in Fig. 1. In this way the mem-

bers 34 form bearings on each side of the latch or trigger arm 29 which may be rigidly secured in the substantially cylindrical body 30 of this latch so as to control its movements, the latch being normally held in this retaining position by suitable spring action as by the spring 32 acting between the pin 31 on the latch and a stationary pin, such as 33, as shown in Figs. 1 and 2. It is advantageous to have this spring actuated 75 latch engage the detent member in such way that under the influence of the spring or weight used to drive the device the force of such a retaining spring or weight is more or less neutralized, which to a corresponding extent makes the releasing or actuating operation of the thermostat or controlling mechanism more efficient and sensitive, especially where the action of the retaining spring also tends to counteract the restraining pressure of the detent forcing the latch against its bearings. This detent mechanism may have any suitable reducing levers or devices to reduce the requisite restraining force of the controlling mechanism of 90 any such alarm or fire protection device, and for instance this latch arm may have its end 28 co-operate with the end 23 of a suitable catch arm 21 which may have its intermediate portion 22 pivoted about the pin 95 26 in the supporting bracket 24 secured to the frame. This detent member may also be given a self-releasing tendency as by interposing a spring, such as 25, between this catch arm and its supporting or bearing member, the end of the spring being, if desired, extended through the hole 27 in this support. The end 20 of this catch arm may as indicated in Fig. 3 be given a knife edge or tapering form to reduce friction and 100 may co-operate with the end of the release arm 15 actuated by the detector diaphragm in any suitable way, as through the light pin 12 guided in the member 13 in the frame and normally held in engagement with the 110 diaphragm by the action of the head or end 14 of this release arm which is normally spring pressed against it as by the spring 18. This spring may be arranged around the pivot 17 on which the bearing portions 115 or lugs 16 of the release arm are supported and held in position in the bearing bracket or support 19 formed on or secured to the frame in any desired way. This arrangement of detent members or reducing levers 120 preferably having as indicated a spring releasing action makes the device quite sensitive and enables a relatively light air pressure on the detector diaphragm to successively release the elements of this detent 125 mechanism so as to allow the rotation of the vibrator disk which correspondingly actuates the alarm diaphragm 79.

It is advantageous to have a resetting device for resetting the various parts of this 130

detent mechanism and this resetting device may advantageously be combined with the winding means where a spring or weight motor is employed. For this purpose a 5 resetter arm, such as 43, may be pivoted about the pin or support 39 and normally held in the inoperative position indicated in Fig. 2 by the spring 49, the end 23 of the catch arm being preferably formed with an 10 inclined portion 105 to assist the end 28 of the latch arm to ride over it. A projecting portion of this resetter arm may be periodically engaged by any one of the moving parts during the winding of the 15 spring or weight so that this resetter arm is thereupon swung upward sufficiently so that it engages and successively restores the various 20 detent devices to their set or holding position. This resetting action may be effected by suitable resetting projections or portions on this resetter arm, such as the upstanding portion 44 adapted to engage the detent arm 29 and throw it up into its 25 full line position in Fig. 2, another portion of the resetter, such as the curved end of this arm 43 thereupon engaging the catch arm 21 to throw its end 23 into the path of this detent arm and simultaneously throw its other end out over the end of the release 30 arm 15 so as to interlockingly engage therewith as shown in Figs. 1 and 3, provided, of course, the diaphragm and release arm are then in their normal holding position shown. This resetter arm may be conveniently actuated by a resetter lug or projection, such as 53, on the winding sleeve or 35 element 54, which may be connected with the winding handle 59 as by the screw joint 58 shown in Fig. 4. When this sleeve and 40 resetter lug are moved in the direction of the arrow in Fig. 2, the lug is brought into engagement with the resetter dog or projection 50 which may be pivoted about the pin 51 on the end 46 of the resetter arm so as to oscillate this resetter arm to the desired 45 extent before the lug slips off the end of this dog. It is of course desirable to allow relatively free retrograde movement of these parts where the winding sleeve is revolved 50 during the emergency actuation of the device and this may be effected by having the resetter dog free to swing on the resetter arm under these conditions, so that the spring 48 is thereby extended as the end 47 of this dog is withdrawn from the pin 52 in the resetter arm. It is desirable to have a suitable lost motion connection between 55 this winding sleeve and the pinion such as 60 actuated thereby which may thus be permanently in mesh with the driving wheel 61. This may be effected by having the pinion secured to the winding arbor 57 and having a pin such as 56 secured to this arbor and loosely engaging one or more slots 55 in the 65 winding sleeve so as to allow ample back lash or lost angular motion between these parts and prevent the resetter lug 53 interfering with the return of the resetter arm 43 to its inoperative position shown in full lines in Fig. 2. Either this lug snaps past 70 the resetter dog 50 if the sleeve is turned to that extent, or if the forward winding movement in the direction of the arrow stops at such point that the resetter lug is still in contact with the dog the spring 49 throws 75 back the resetter lug and connected winding sleeve sufficiently to allow the resetter arm to return to its normal inoperative position, the amount of lost motion provided between the pin 56 and slot 55 being ample for this 80 purpose.

It is quite desirable to have a distinctive type or character of sound produced by the audible alarm device used in this connection, and where, for instance, the diaphragm type 85 of alarm signal is employed this may be effected by periodically or occasionally changing the pitch or intensity of the diaphragm vibration or of the resultant air vibrations or both through any suitable means. For 90 some purposes it is sufficient to have the pitch of the teeth on the vibrator disk or member vary more or less and as indicated in Fig. 1 these teeth may more or less gradually increase in pitch from the relatively closely spaced teeth 74 to the widely spaced teeth 75 so that for every revolution of the disk a gradual change of pitch is thus effected. In some cases either instead of or in connection with such a pitch variation of 100 the teeth and resulting diaphragm sound, the intensity of the vibration may be periodically varied as by having some of these teeth project farther than others in a more or less progressive fashion as indicated in 105 Fig. 1 where the closely spaced teeth 74 project farther toward the contact member 81 connected to the diaphragm than the widely spaced teeth 75. Any other suitable arrangements may of course be used for effecting such a change of pitch or intensity of the sound. As shown in Fig. 6 the speed of the vibrator disk 73 which may in this instance have uniformly spaced teeth 74, may, if desired, be periodically retarded by the 110 action of a retarder lever or member 99 pivoted, for example, about the pin 97 in the bracket 96 secured to the frame in any suitable way and occasionally thrown into engagement with the vibrator disk as by the 115 retarder cam 98 on any of the moving parts of the device, as for instance on the intermediate shaft 67. When this cam comes into contact several times a second, for instance, with the bearing member or plate 120 109 on the retarder lever, it forces the other thin resilient end of this lever lightly into engagement with the vibrator disk so as to somewhat retard its speed and periodically 125 reduce the pitch of the alarm signal pro- 130

duced by the engagement of these teeth 74 with the contact member 81 secured to the signal diaphragm. Another regulating device which may be used in connection with 5 or in addition to those previously mentioned is by throttling or damping in any suitable way the air vibrations produced by the alarm as by using any suitable throttling damper to more or less close the horn aperture in a periodic or intermittent manner. As shown in Fig. 6 the special horn member 101 may be secured to the front plate 77 and may have secured thereto an apertured plate 85 having a series of apertures 86 15 formed therein in any suitable way. A movable damper or regulator plate or member 87 may coöperate therewith and be formed with corresponding apertures 88 which may normally register with the apertures 86 to 20 allow the maximum emission of sound while when the damper plate is moved so that its slot 89, for instance, moves with respect to the screws or pins 100 these apertures may be more or less closed and the audible alarm 25 signal considerably reduced or extinguished in a characteristic way so as to give a recurrent or intermittent characteristic alarm signal. This may be effected by a regulator arm or member 91 pivoted, for instance, 30 about the pin 95 in the bracket 96 and having its end projecting through the aperture 90 in the damper plate. Normally the spring 94 on this arm may hold the damper plate in this open position while when the regulator cam or projection 93 on the shaft 67 35 swings around into engagement with the cam plate or follower 92 on the regular arm, this arm is moved outward so as to more or less close these damper apertures and then 40 allow them to open in a gradual manner for this purpose.

This invention has been described in connection with a number of illustrative embodiments, forms, arrangements, proportions, parts, materials and methods of use, 45 to the details of which disclosure the invention is not of course to be limited, since what is claimed as new and what is desired to be secured by Letters Patent is set forth in the 50 appended claims:

1. In automatic fire alarm devices, a frame, a metallic air chamber secured to said frame and comprising an apertured support plate, a detector diaphragm co- 55 operating therewith; a guard plate secured to said support plate to clamp said detector diaphragm in position and limit its motion, a front plate secured to said frame and formed with a horn, a signal diaphragm 60 secured to said front plate in coöperation with said horn; a casing removably secured to said frame to substantially cover the space between said air chamber and said front plate and formed with supporting de- 65 vices adapted to be secured to a wall, a

spring motor mounted in said casing and comprising a toothed vibrator having a detent wheel, a contact member connected to said signal diaphragm and coöperating with said vibrator and detent mechanism co- 70 operating with said detent wheel and comprising spring releasing members adapted to be actuated by said detector diaphragm.

2. In automatic fire alarm devices, a frame, a vented metallic air chamber secured 75 to and forming one end of said frame and comprising an apertured support plate, a metallic detector diaphragm secured to said support plate and closing one end of said air chamber, a front plate secured to said frame and formed with a horn, a signal diaphragm secured to said front plate in co-operation with said horn, a spring motor mounted on said frame and comprising a toothed vibrator coöperating with said signal diaphragm, detent mechanism controlling said vibrator and comprising spring 80 releasing members adapted to be actuated by said detector diaphragm.

3. In automatic fire alarm devices, a frame, a vented air chamber secured to said frame adjacent one end thereof, a detector diaphragm closing one end of said air chamber, a signal diaphragm, a spring motor mounted on said frame and comprising a toothed vibrator having varying pitch teeth 90 coöperating with said signal diaphragm, detent mechanism controlling said vibrator and adapted to be actuated by said detector diaphragm.

4. In fire alarm devices, a thermostat, an audible alarm actuated by said thermostat and comprising a toothed vibrator and a co- 95 operating diaphragm and means to periodically vary the quality of the alarm signal produced by said diaphragm and comprising teeth spaced irregularly around said vibrator.

5. In fire alarm devices, a thermostat, an audible alarm actuated by said thermostat 100 and means to periodically vary the pitch and intensity of the resulting sound vibrations to give a characteristic alarm signal.

6. In fire alarm devices, a thermostat, an audible alarm actuated by said thermostat 110 and means to repeatedly vary the intensity of the resulting sound vibrations to give a characteristic alarm signal.

7. In fire alarm devices, a thermostat, an audible alarm actuated by said thermostat 120 and comprising a toothed vibrator and a co- operating diaphragm and means to periodically vary the intensity of the alarm signal produced by said diaphragm and comprising teeth spaced around said vibrator and projecting therefrom to different extents to periodically vary the intensity of the vibration of said diaphragm.

8. In automatic fire alarm devices, a thermostat, an audible alarm signal, a motor to 130

- operate said alarm, detent mechanism to normally restrain said motor and comprising detent members adapted to be actuated by said thermostat, a spring pressed resetting arm coöperating with said detent members to reset the same in interlocked restraining position and winding devices for said motor comprising a winding sleeve having a resetter lug to actuate said resetter arm as said winding sleeve is operated during the winding movement, a resetter dog loosely pivoted on said resetter arm and adapted to be engaged by said resetter lug and a spring normally holding said resetter dog in position with respect to said arm, a winding member coöperating with said winding sleeve and a lost motion connection between said winding member and sleeve. 9. In automatic fire alarm devices, a thermostat, an audible alarm signal, a motor to operate said alarm, detent mechanism to normally restrain said motor and comprising detent members adapted to be actuated by said thermostat, a spring pressed resetting arm coöperating with said detent members to reset the same in interlocked restraining position and winding devices for said motor comprising a resetter lug to actuate said resetter arm as said winding devices are operated during the winding movement, a resetter dog loosely pivoted on said resetter arm and adapted to be engaged by said resetter lug and a spring normally holding said resetter dog in position with respect to said arm. 10. In automatic fire alarm devices, a thermostat, an audible alarm signal, a motor to operate said alarm, detent mechanism to normally restrain said motor and comprising detent members adapted to be actuated by said thermostat, a resetting arm coöperating with said detent members to reset the same in interlocked restraining position and winding devices for said motor comprising a resetter lug to actuate said resetter arm as said winding devices are operated during the winding movement. 11. In fire alarm devices, a signal diaphragm, a motor and connected toothed vibrator coöperating with said diaphragm, detent mechanism to normally restrain the operation of said vibrator and comprising detent members adapted to be actuated by controlling devices, a resetting arm coöperating with said detent members to reset the same in interlocked restraining position and winding devices for said motor comprising a resetter member to repeatedly actuate said resetter arm during the winding movement and means to prevent undesirable engagement of said resetter member and resetter arm during the unwinding movement of said motor. 12. In fire alarm devices, a signal dia-
- phragm, a motor and connected toothed vibrator coöperating with said diaphragm, detent mechanism to normally restrain the operation of said vibrator and comprising detent members adapted to be actuated by controlling devices, a resetting arm coöperating with said detent members to reset the same in restraining position and winding devices for said motor comprising a resetter member to repeatedly actuate said resetter arm during the winding movement. 13. In fire alarm devices, a thermostat, an audible alarm signal, a connected alarm motor comprising a detent wheel and detent mechanism to normally restrain the operation of said alarm motor and adapted to be actuated by said thermostat, said detent mechanism comprising a detent coöperating with said detent wheel and a releasing spring engaging said detent and opposing the angular and lateral force of said detent wheel thereon. 14. In fire protection devices, a controlling device, an emergency fire protection device and coöperating motor means comprising a detent member and detent mechanism to normally restrain the operation of said motor means and adapted to be actuated by said controlling device, said detent mechanism comprising a detent coöperating with said detent member and a releasing member engaging said detent and opposing the force of said detent member thereon. 15. In automatic fire alarm devices, a rate-of-rise air thermostat, an audible alarm, a motor to operate said alarm, detent mechanism to normally restrain said motor and comprising detent members adapted to be actuated by said thermostat, a resetting arm coöperating with said detent members to reset the same in interlocked restraining position and energizing devices for said motor comprising a resetter lug to actuate said resetting arm as said motor is energized. 16. In automatic fire alarm devices, a compensated rate-of-rise air thermostat, an audible alarm, a motor to operate said alarm, mechanism to normally restrain said motor and releasable by said thermostat, means for setting said mechanism and energizing devices for said motor comprising means to actuate said setting means as said motor is energized. 17. In automatic fire alarm devices, a thermostat, an alarm, a motor to operate said alarm, mechanism to normally restrain said motor and comprising members adapted to be actuated by said thermostat, setting means coöperating with said members to set the same in restraining position and energizing devices for said motor comprising means to actuate said setting means as said motor is energized.

ERNEST A. LOWE.
